UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING MACHINE.

Application filed July 18, 1921, Serial No. 485,690. Renewed June 16, 1927.

This invention relates to mining machines of the type employed for cutting kerfs in a mine face.

It has for an object to provide a convertible machine which is readily adaptable to either the longwall or the room and pillar method of mining, and which may be operated as either an undercutter, to insert a kerf in the mine face at or near the bottom thereof, or as an overcutter, to insert a kerf at an elevation above the bottom. Another object of the invention is to provide improved mining machine feeding means wherein a material reduction in the number of necessary parts is combined with an increased range of adaptability for different classes of work. A further object of the invention is to provide improved power transmitting mechanism for actuating the feed operating member carried by a mining machine, which mechanism is of relatively simple and compact construction while providing for an extremely convenient and accurate control capable of producing a wide range of movements. A still further object of the invention is to provide improved means whereby the feed actuating mechanism of a mining machine may be employed to furnish the power for propelling the truck on which said machine is transported from place to place.

The foregoing and other objects of the invention, together with means whereby the same may be carried into effect, will best be understood from the following description of one form or embodiment thereof illustrated in the accompanying drawings, in which:

Fig. 1 is a side elevation, partially broken away, of the complete machine.

Fig. 2 is a plan view thereof.

Fig. 3 is a rear elevation.

Fig. 4 is a detail plan view of one of the rear corners of the machine, showing one of the rotatable guide members for the flexible feeding member and means for mounting the same.

Fig. 5 is a vertical section on the line 5—5 of Fig. 3.

Fig. 6 is a longitudinal vertical section, on an enlarged scale, of the rear end of the machine, taken substantially on the line 6—6 of Figs. 2 and 7.

Fig. 7 is a transverse section taken substantially on the line 7—7 of Fig. 6.

Fig. 8 is an enlarged longitudinal vertical section of the head, taken substantially on the line 8—8 of Fig. 2.

Fig. 9 is a similar section partially in elevation, on a smaller scale, showing the head inverted to adapt the machine for overcutting.

Figs. 10 and 11 are diagrammatic plan views illustrating the operation of the machine in room and pillar work.

Figs. 12 and 13 are similar views illustrating the use of the apparatus as a longwall machine.

Fig. 14 is a diagrammatic side elevation illustrating the use of the machine in overcutting.

Fig. 15 is a diagrammatic rear elevation illustrating the arrangement of the flexible feeding member and the guide members for feeding the machine in opposite directions.

Fig. 16 is a diagrammatic plan view of the rear end of the machine, illustrating the operation of loading the machine upon a truck.

Fig. 17 is a simplified partial plan view showing the machine mounted upon the truck and illustrating the connections for propelling the latter.

Referring to Fig. 1, the machine illustrated therein comprises a frame or casing 25 sliding upon its bottom over the mine bottom, herein upon a shoe 26, said frame or casing having at its forward end a hollow head 27 carrying a swinging or pivotally mounted cutter bar 28 provided with the usual cutter chain 29. The shoe 26 extends beyond the casing 25 and beneath the head 27 so as to provide a base for the machine throughout substantially its entire length.

The frame or casing 25 is formed at its forward end with a substantially circular rib or projection 40 (Fig. 8) which is received in a correspondingly shaped opening in the rear wall of the head 27, whereby the rear end of said head is seated on and supported by said projection. Within the casing 25 is a motor (not shown) of any suitable type

for supplying the necessary power for operating the cutter chain 29 as well as the feeding mechanism hereinafter described for moving the machine across the face to cause said cutter chain to cut a kerf therein. The shaft 39 of said motor extends coaxially through the projection 40 and into the rear end of the head 27 so as to cooperate with

mechanism hereinafter described within said head. The cutter bar 28 is eccentrically disposed with respect to the common axis of the projection 40 and motor shaft 39, 5 while the head 27 is invertible about said axis and is detachably secured to the forward end of the casing 25 by means permitting the attachment of said head to said casing either side up, that is to say, either 10 in the undercutting position shown in Figs. 1 and 8, with the cutter bar at the bottom, or in the overcutting position shown in Figs. 9 and 14 and indicated in dotted lines in Fig. 1, with the cutter bar at the top. The 15 securing means, as herein shown, comprise vertical flanges on the head 27 adapted to be attached to the forward end of the casing by bolts or screws 31 symmetrically arranged with respect to the axis of the motor 20 shaft 39 and projection 40.

For convenience of description, the undercutting position of the head will be assumed as the normal position thereof, and the relative location of the several parts will be 25 described with reference to this position.

Referring particularly to Fig. 8, the head 27 is divided on a substantially horizontal plane into upper and lower sections 49 and 50, respectively, said sections being normally secured together to form a substantially unitary head by suitable means, herein shown as cap 30 screws 51. The lower section 50 is provided at its under side with a vertically disposed substantially cylindrical boss or sleeve portion 32 upon which is pivotally mounted an arm 33 carrying the cutter bar 28, whereby said cutter bar is mounted to swing in a substantially horizontal plane about the axis of said boss. Said lower section 50 is further 35 formed with a horizontally disposed arcuate flange 34 disposed concentric with the boss 32, while the arm 33 is provided with a vertically disposed flange 35 formed with an ear 36, said arm 33 and ear 36 having aligned 40 openings adapted in different angular positions of said arm and cutter bar to register with openings 37 in the flange 34 and to receive a locking pin 38, whereby said arm and cutter bar may be locked in any position of 45 angular adjustment.

Within the head 27 is located mechanism driven from the motor shaft 39 for actuating the cutter chain 29, said mechanism being of such a character as to be operatively 50 engageable with said motor shaft in either position of said head. As herein shown, the motor shaft 39 has keyed thereto at its forward end, and held in place by means of a screw 52, a bevel pinion 41 which meshes 55 with a bevel gear 42 having a hub rotatably mounted on a sleeve 43 splined to an upright shaft 44 and normally secured thereto, as by a screw 53. The shaft 44 is journaled at its lower end in an antifriction step bearing 45 carried by the lower head section 50,

while the sleeve 43 thereon is journaled at its upper end in an antifriction step bearing 46 carried by a cover plate 47 secured to the upper head section 49 by cap screws 48 and closing a circular opening in said head section disposed coaxially with the shaft 44. By removing the cap screws 48, the cover plate 47 may be removed, thereby permitting adjustment or removal of the bearing 46 and sleeve 43 without disconnecting the head sections. The gear 42 may be operatively connected with the sleeve 43, to rotate said sleeve and the shaft 44 to which it is secured, by means of a clutch hub 54 mounted to slide upon the hub of said gear and having internal clutch teeth which engage cooperating external clutch teeth formed on said hub and on a flange 55 on said sleeve. The clutch hub 54 is operated by a clutch fork 56 carried by a rock shaft 57 journaled in the head section 49 and provided exteriorly thereof with a clutch controlling lever 58 (Figs. 1 and 2). The shaft 44 is provided below the gear 42 with a preferably integral pinion 59 which meshes with a gear 60 having a hub journaled in an antifriction bearing 61 in the upper end of the boss or sleeve portion 32. The gear 60 is connected by longitudinal bolts 62 to a coupling ring 63 having oppositely projecting teeth 64 and 65 adapted to engage respectively the hub of said gear and the hub of the sprocket 66 for actuating the cutter chain 29, said cutter chain sprocket being also connected by longitudinally extending bolts 67 with said coupling ring 63 and having its hub mounted in an antifriction bearing 68 carried by the lower end of the boss or sleeve portion 32. Interposed between the bearings 61 and 68, and surrounding the coupling ring 63, is a split bushing ring 69 engaging an internal flange 70 on the sleeve or boss 32. With this construction it will be seen that, by removing the bolts 62 or 67, either the gear 60 or the cutter chain sprocket 66 may 105 be removed independently of the other and without disturbing the mounting of the other.

Extending coaxially through the gear 60 and cutter chain sprocket 66 is a vertical 110 stud 71 having at its lower end an axially disposed threaded socket 76 to receive the upper end of a threaded stud 72 carried by a cover plate or disk 73 seated in a coaxially disposed opening in the shoe 26 and secured therein by a clamping plate or disk 74 attached to said cover plate by cap screws 75, said plate 74 having a boss 81 on which the lower end of the stud 71 is seated. At 115 its opposite or upper end, the stud 71 is formed with a second axially disposed threaded socket 77 similar to the socket 76 and engaged by a threaded stud or screw 78 carried by a cover plate 79 secured, as by cap screws 80, to the upper head section 49 and 120

- normally closing a circular opening therein which is coaxially disposed with respect to the stud 71. The upper head section 49 is recessed adjacent the cover plates 47 and 79 to permit said plates, together with the heads of the screws 48, 78 and 80 to be positioned substantially flush with or slightly within the upper surface of said head section.
- 10 The parts being in the position shown in Figs. 1 and 8, thereby adapting the machine for undercutting, in order to invert the head 27 so as to arrange the machine for overcutting, as shown in Figs. 9 and 14 and as indicated in broken lines in Fig. 1, the screws 78 and 80 and the cover plate 79 are first removed, thereby permitting the stud 71 to be unscrewed from the stud 72 and withdrawn through the top of the head. The cap screws 75 are then removed to disconnect the plates 73 and 74, the plate 73 with its attached stud 72 being withdrawn from the bottom of the machine. The cover plate 79 and screws 80 are then replaced, the bolts 31 removed, the head disengaged from the projection 40 and inverted (causing the cover plate 79 to be seated and supported on the boss 81 of the plate 74), and the bolts 31 replaced in order to secure the head 27 to the casing 25 in its new position. The cover plate 73 is then replaced and secured to the plate 74 by a cap screw 75, causing the stud 72 carried by said cover plate to project upwardly through the plates 74 and 79, whereupon the stud 71 may be re-inserted and re-engaged at its lower end with said stud 72 and the screw 78 inserted into the socket 77, the parts then being in the overcutting position shown in Figs. 9 and 14.
- 40 It will be observed that the gear 60 and cutter chain sprocket 66 are journaled in the head by means of the bearings 61 and 68, clutch ring 63, and bolts 62 and 67 independently of the stud 71, so that the removal of said stud does not disturb the mounting of these parts or the cooperative connection of the gear 60 with the sprocket 66 and pinion 59, the mechanism being carried by and inverted with the head as a unit.
- 45 The function of the stud 71 is to assist in centering and positioning the parts and, more particularly, to serve as a brace and connecting means between the head 27 and shoe 26, so as to hold these parts in properly spaced relation and otherwise to position the same relative to each other, particularly when the head is in the undercutting position shown in Fig. 8. When the head is in the overcutting position shown in Fig. 9, the cover plate 79 engages the boss 81 on the plate 74 as above explained, but the stud 71 serves as means for connecting these parts and holding the same against lateral movement.
- 55 During the cutting operation the machine
- is fed along the mine face by a flexible feeding member, herein shown as a chain 82 (Fig. 2), which passes about suitably arranged rotary guide members 83 and 84 (hereinafter more fully described) at the rear end of the machine and cooperates with a rotary feed operating member 85 herein shown as located at the rear end of the machine and disposed with its axis horizontal as in my prior application for Letters Patent, filed June 5, 1919, Ser. No. 301,917.
- 60 In accordance with the present invention, and as shown in Fig. 6, the feed operating member 85 is formed with the hub 89 (Fig. 6) which is rotatably mounted in antifriction bearings 90 and 90^a carried respectively by a horizontal, longitudinally disposed cylindrical boss or sleeve portion 91 projecting rearwardly from the casing 25 and in a bracket or keeper 148 (Figs. 2, 3, and 6) secured to the rear end of said casing. In addition to the guide members 83 and 84, and as in my prior application for Letters Patent, filed December 26, 1919, Ser. No. 347,571, the machine is herein shown as provided at its forward end with an auxiliary rotary guide member 86 (Fig. 2) carried by a bracket 87 detachably secured to the head 27 by a pin or bolt 88 engaging one of the openings 37 in the flange 34. The rotary feed operating member 85 is actuated from the motor by suitable connections providing a reversible variable speed drive for said feed operating member. As herein shown, said connections are as follows:
- 65 Referring to Fig. 6, the motor shaft 39 is provided at its rear end with a preferably integral pinion 92 which meshes with an internal gear 93 rotatably mounted on a longitudinally disposed main transmission shaft 94 journaled at its ends in antifriction bearings 95 and 96 carried by suitably disposed portions of the machine frame or casing 25. The gear 93 is adapted to be connected to the shaft 94 by means of a friction clutch, herein shown as of the multiple disk type comprising a series of clutch disks 97, alternate disks being connected respectively with said gear 93 and with a sleeve 98 splined to the shaft 94 and longitudinally movable thereon, to engage or disengage the clutch, by means of a clutch fork 99 carried by a transverse rock shaft 100 provided with an arm 101 which is connected to an operating rod 102 (see Figs. 3 and 7) extending to the rear of the machine and provided with a suitable operating handle. The clutch disks 97, in addition to constituting means for operatively connecting and disconnecting the gear 93 and shaft 94, serve as a yielding transmission element whereby the power transmitted from the motor shaft 39 to the feed operating member 85, through the positive driving connections hereinafter described, may be limited, in order to pre-

vent excessive strain upon the mechanism in the event of abnormal resistance to the machine, as when an unusually hard spot or other obstruction is unexpectedly encountered in cutting.

Rotation of the shaft 94 is transmitted to the feed operating member 85 by means of reversible variable speed transmission devices adapted to rotate said member at 10 either of two speeds in one direction or at either of two speeds in the opposite direction, the driving speeds in one direction being relatively higher than those in the opposite direction. In accordance with the 15 present invention, said mechanism includes a countershaft 103 disposed with its axis in substantially the same vertical plane as the axis of the shaft 94 and mounted in antifriction bearings 104 carried by suitably 20 disposed portions of the machine frame or casing, a second countershaft 105 alined with the countershaft 103 and journaled in antifriction bearings 106 carried by a boss or sleeve portion 135 formed on said frame or 25 casing, means for operatively connecting the countershaft 105 with the feed operating member 85 for rotating the latter, means for operatively connecting the countershaft 103 with the main transmission shaft 94 30 whereby said countershaft may be rotated at relatively high or relatively low speed with respect to the speed of rotation of said shaft 94, and means for operatively connecting the countershaft 105 with the countershaft 103 whereby said countershaft 105 35 may be driven in the same direction and at the same speed as the countershaft 103 or in the opposite direction at a lower speed. As herein shown, these connections are as 40 follows:

For operatively connecting the countershaft 105 with the feed operating member 85, whereby the latter is rotated by the former, said countershaft 105 is provided at 45 its rear end with a preferably integral pinion 107 which meshes with an internal gear 108 secured to or formed integral with the feed operating member 85 and extending through a circular opening in the rear end 50 of the casing 25 about the sleeve or boss 91.

For operatively connecting the shaft 94 with the countershaft 103 in order to rotate the latter at a variable speed, the following mechanism is herein shown. The clutch sleeve 98 is provided with a preferably integral pinion 109 which meshes with a gear 110 having a hub 111 which is keyed to a sleeve 112 rotatably mounted on the countershaft 103. Fast upon the shaft 94 is a 55 pinion 114 smaller than the pinion 109 and meshing with a gear 115 which is larger than the gear 110, said gear 115 having a hub 116 keyed to a sleeve 117 also rotatably mounted 60 on the countershaft 103. The sleeves 112 and 117 may be alternatively connected with

the countershaft 103 to cause said countershaft to be driven from the shaft 94 at a relatively high speed through the pinion 109 and gear 110 or at a relatively low speed through the pinion 114 and gear 115 by 70 means of a clutch hub 113 splined to the countershaft 103 between the sleeves 112 and 117, said clutch hub being oppositely movable from the central or neutral position shown in Fig. 6 to cause clutch teeth 75 thereon to engage complementary clutch teeth formed on said sleeves, respectively. To the above ends, the clutch hub 113 is operated and controlled by a clutch fork 118 carried by a transverse rock shaft 119 provided with an arm 120 connected with an operating rod 121 extending to the rear end of the machine.

In the construction shown, the countershafts 103 and 105 may be directly connected 85 for rotation in unison by means of a clutch hub 122 splined to the countershaft 105 and longitudinally movable thereon in one direction from the neutral position shown in Fig. 6 to cause internal clutch teeth formed 90 thereon to cooperate with the teeth of a pinion 123 fast upon the end of the countershaft 103. The clutch hub 122 is operated by a clutch fork 124 carried by a transverse rock shaft 125 provided with an arm 126 95 connected with an operating rod 127 extending to the rear end of the machine.

For operatively connecting the countershafts 103 and 105 to cause the latter to be driven in a direction opposite to the direction of rotation of the former and at a reduced speed, the following mechanism is 100 herein shown. The pinion 123 meshes with a gear 128 (Fig. 7) carried by a stud 129 suitably supported in the machine frame, said gear 128 having connected thereto for rotation therewith a pinion 130 meshing with a gear 131 (see also Fig. 6) keyed to a sleeve 132 rotatably mounted on the shaft 94. The sleeve 132 carries a preferably integral pinion 133 which meshes with a gear 134 105 rotatably mounted on the countershaft 105 and on the boss or sleeve portion 135 in which the bearings 106 are carried. The gear 134 is provided with a hub formed with 110 clutch teeth or elements 136 adapted to be engaged by the clutch teeth or elements on the clutch hub 132 when the latter is moved from its neutral position in the direction opposite to that in which it is moved to engage the pinion 123, as above described. As 115 will now be seen, when the clutch hub 122 is moved into the position to cause the clutch elements thereon to engage the clutch elements 136, the gear 134 will be operatively connected with the countershaft 105, thereby causing said countershaft to be driven from the countershaft 103, through the gearing 123, 128, 130, 131, 133 and 134, in a reverse direction and at a reduced speed.

As in my application for Letters Patent, filed June 18, 1921, Ser. No. 478,473, the mechanism for actuating the feed operating member 85 is also employed to operate mechanism for propelling the truck upon which the machine is transported from place to place about the mine. As shown in Fig. 17, said truck comprises a body 137 mounted on wheels 138 whose axles are connected by chain and sprocket gearing 139 with a propelling shaft 140 extending transversely of the truck body and suitably journaled therein. The shaft 140 is provided intermediate its ends with a bevel gear 141 which meshes with a bevel gear 142 suitably journaled on said truck body to rotate about a longitudinal axis. The gear 142 is connected by a universal joint 143 with a coupling member 144. In accordance with the present invention, the coupling member 144 is provided with suitable clutch elements adapted to cooperate with complementary clutch elements on a head 145 formed on a shaft 146 (Fig. 6) passing axially through the hub 89 of the feed operating member 85 and journaled therein, said shaft having keyed thereto at its inner end a gear 147 meshing with the pinion 107, whereby the truck propelling head 145 is actuated from the countershaft 105. The head 145 is coaxially disposed with respect to the feed operating member 85, is substantially housed in the bracket 148, and is journaled in the bearing 90^a carried by the latter.

The rotary guide members 83 and 84, which are disposed upon vertical axes, are arranged substantially at the upper and lower rear corners of the frame or casing 25 and are adapted to be received in recesses 150 formed in said frame or casing at these points. Said members, in the construction shown, are mounted on studs 151 each of which is supported by an arm 152 (see particularly Figs. 3, 4, and 5) pivoted to an ear or lug 153 projecting horizontally from the frame or casing 25, whereby said guide members may be swung outwardly into the position shown in full lines in Fig. 4 or inwardly into the recesses 150 as shown in broken lines in the same figure. The inward and outward positions of said guide members are fixed by stop lugs 154 and 155 adapted to engage the arms 152 when the latter are swung inwardly or outwardly, respectively.

Recesses 150 and supporting lugs or ears 153 are symmetrically disposed at both sides of the rear end of the machine, and a single pair of guide members 83 and 84 is employed, said guide members being detachably secured to the ears or lugs 153 and being transferable or interchangeable from one side of the machine to the other in accordance with the conditions of use. To this end, in the embodiment of the invention shown, the following construction is provided. The arms 152 are provided with telescoping studs 160 (see particularly Fig. 5) which are rotatably received in alined openings 161 in the ears or lugs 153, one of said studs having a preferably reduced end portion 162 which is received in a coaxially disposed socket 163 in the other and is detachably retained therein by a set screw 164 which engages an annular groove 165 in said end portion 162. By the foregoing construction it will be seen that the arms 152 will be retained in position on the ears or lugs 153 but may swing independently thereon, while, by removing the set screw 164, the studs 160 may be separated and the arms 152 with the guide members 83 and 84 carried thereby detached and transferred to the opposite side of the machine where they may be reattached in the same manner and in the same relative positions.

By reference to Figs. 1 and 2, it will be observed that by reason of the horizontal disposition of the axis of the feed operating member 85 the portion or groove of this member which receives the flexible feeding member 82 is disposed substantially in a vertical plane lying relatively close to the rear end of the machine. The axes of the guide members 83 and 84 being vertical, or transverse to the axis of the feed operating member 85, the guide portions or grooves of the latter members lie in substantially horizontal planes which, in accordance with the present invention, are substantially tangential to the guide portion or groove of the feed operating member 85 at the top and bottom thereof respectively, said feed operating member being of a diameter substantially equal to the vertical distance between said planes. Moreover the housing of said members 83 and 84 in the recesses 150 permits the guide portions or grooves of said members to be tangential to a vertical plane passing through the guide portion or groove of the feed operating member 85, at the inner side of said plane, notwithstanding the proximity of said plane to the rear end of the machine, while the movable mounting of said guide members permits them to be swung outwardly across said plane into positions tangential thereto at the outer side thereof. It will, therefore, be seen that the portions of the flexible feeding member 82 extending between the feed operating member 85 and the guide members 83 and 84 may lie substantially in a common vertical plane with the guide portion or surface of said feed operating member, so as to permit said flexible feeding member to run smoothly. It will also be seen that the flexible feeding member may engage the guide members 83 and 84 either externally or internally, depending upon the requirements imposed by the direction of pull or reaction of said flex-

ible member upon the machine, as will hereinafter be apparent.

In addition to the regular rotary guide members 83 and 84 and the auxiliary guide member 86, there is preferably provided a second auxiliary guide member 175 (see Fig. 16) which is rotatably mounted on one end of an arm 176 having at its opposite end a hook 178 adapted for detachable engagement with the opening 161 in any one of the ears or lugs 153, whereby said arm is adapted to swing freely on said lug. The auxiliary guide member 175 may be conveniently employed for the purpose of loading the machine upon the truck, the flexible feeding member 82 being at this time, for example, passed about the outer side of the guide member 84, thence about the feed operating member 85, thence about the inner side of the guide member 83 to the outer side thereof, and finally about the auxiliary guide member 175 from which it may be led to the usual chain fork or other suitable fixed abutment 180 on the truck body 137.

As is usual in machines of this type, the cutter bar 28 may be swung about its axis on the head 27, herein the axis of the boss or sleeve portion 32, by engagement of the flexible feeding member 82 with the flange 35, or with a suitable hook attached thereto, said flexible feeding member passing from said flange about the guide members 83 and 84 and feed operating member 85 which is actuated to draw upon the flexible feeding member and swing said bar. For room and pillar work, the cutter bar 28 is swung into its longitudinal position, as shown for example in Fig. 10, and is locked in such position by the pin 38. With the bar in this position, the machine is then disposed and connected as indicated in dotted lines in Fig. 10 and sumped into the face by an operation of the feed operating member to draw in the portion of the feed chain extending between the machine and the far rib, the speed being varied by adjusting the gearing to give either a fast feed or slow feed as the cutting conditions require and the feed further being subjected to control when desired by slipping the friction. During this sumping cut, the other extremity of the feed chain may be left slack or connected to a jack at the opposite rib as desired. After this sumping cut, in order to cut toward the left, as shown in Fig. 10, the guide members 83, 84, and 86 are disposed at the left side of the machine, or the direction toward which the cut is to be made, and the flexible feeding member 82 is anchored at its forward end at the left end of the mine face, passes about the inner side of the guide member 86, thence longitudinally of the machine at the left or forward side thereof, thence (for undercutting and as shown in Fig. 10) about the outer side of the guide member 84

(which at this time is housed in its recess 150), thence about the feed operating member 85, and finally about the inner side of the guide member 83 (which at this time is swung outwardly) whence said flexible feeding member extends toward the right to an anchor at the right hand rib in a usual manner. In order to sump and cut toward the right, as shown in Fig. 11, the guide members and flexible feeding member will be oppositely arranged, as shown in said figure and as will be understood without further explanation.

The use of the machine in longwall cutting is illustrated in Figs. 12 and 13. For this purpose the cutter bar 28 is swung or sumped from its longitudinal position into a position transverse to the machine at one side or the other thereof in accordance with the direction of cut, as will be familiar to those skilled in the art, the bar being swung about its pivot by connecting one end of the feed chain to the member 35 and actuating the feed operating member to draw in the feed chain at the desired speed until the same assumes the full line position shown, for example, in Fig. 12. When the feed chain is disconnected from the member 35, the bar is preferably locked in position and the feed chain re-arranged for the transverse cut. When cutting toward the right, as shown in Fig. 12, the guide members 83 and 84 are attached to the machine at the side thereof toward the face, and the flexible feeding member 82 is anchored at its right or forward end, passes about one or the other of said guide members at the inner side thereof, thence about the feed operating member 85, and finally about the other of said guide members which serves to hold said flexible feeding member in engagement with said feed operating member. In cutting toward the left, as shown in Fig. 13, the guide members and flexible feeding member will be oppositely disposed as will be clear from the drawings without further explanation.

As above explained, the machine is adapted for either overcutting or undercutting, depending upon the position in which the head 27 is attached to the casing 25. The arrangement of the flexible feeding member with respect to the guide members 83 and 84 is also varied slightly for these different classes of work. In undercutting the forward portion of the flexible feeding member, or that through which the pull is transmitted to the machine, is passed first about the lower guide member 84, or that nearest the kerf in a vertical direction, as indicated in Figs. 10 to 13, the rear end of said flexible feeding member after leaving the feed operating member 85 passing about the upper guide member 83. In overcutting, on the other hand, the forward or pulling end of the flexible feeding member is passed first

about the upper guide member 83, or that nearest the cutter bar when the latter is arranged for overcutting, as indicated in Fig. 14, which illustrates the operation of 5 the machine in room and pillar work, the direction of cut being as in Fig. 10, and the flexible feeding member being otherwise arranged as in the latter figure.

In Fig. 15, the parts are shown in full 10 lines as arranged for a cut toward the left and in broken lines as arranged for cutting toward the right. For longwall cutting both guide members 83 and 84 will be swung outwardly, as shown in Figs. 12 and 13, while 15 for room and pillar work, one of said members will be swung inwardly and the other outwardly, depending upon whether the machine is employed for overcutting or undercutting, as above explained.

20 In all of the cutting operations, it will, of course, be understood that the auxiliary guide member 175 is not used, the same preferably being removed from the machine. It will further be understood that in all long- 25 wall operations whether overcutting or undercutting, the auxiliary guide member 86 is not used and may be removed from the machine or attached to the head 27 in such a position as to be out of the way.

30 From the foregoing, it will be seen that the invention provides a machine adapted for either overcutting or undercutting by either the longwall or the room and pillar method and capable of cutting in either direction and at a speed which is subject to considerable variation and which can be readily controlled, said machine also having provision whereby it is capable of loading itself upon a truck and having means for furnishing the necessary power to propel the truck when so loaded. It will also be seen that this wide adaptability of the machine is obtained by means of relatively simple and compact feed actuating mechanism and 45 by the use of only two regular guide members for the flexible feeding member and two auxiliary guide members (one of which is used only in room and pillar cutting, and the other of which is used only in loading), said members being so mounted as to be transferable on the machine and connectible therewith at a variety of points in accordance with the requirements of the particular feeding movements to be produced. 50 These and other advantages of the invention will, however, be obvious to those skilled in the art without further explanation.

While I have herein shown and described in detail one form which the invention may 55 assume in practice and several ways in which it may be used, it will be understood that the particular constructions, arrangements and uses described and shown have been chosen for illustrative purposes merely, and that the invention may be otherwise

embodied and practiced without departing from its spirit or the scope of the claims hereunto appended.

What I claim as new and desire to secure by Letters Patent is:—

1. In a mining machine, a frame having a forwardly extending mine bottom engaging portion, a head detachably secured to said frame and overlying said portion and adapted to be in part supported thereon, cutting mechanism carried by said head, means permitting the disposition of said head in different positions with respect to said frame whereby cutting in different planes is possible, and means carried by said frame for 70 actuating said cutting mechanism.

2. In a mining machine, a frame having a forwardly extending mine bottom engaging portion, a head overlying said portion and in part supported thereon, cutting 75 mechanism carried by said head, means carried by said frame for actuating said cutting mechanism, and means symmetrically disposed with respect to said actuating means for detachably connecting said head to said frame in different relative positions with respect to the latter.

3. In a mining machine, a frame having a forwardly extending mine bottom engaging portion, a head overlying said portion and in part supported thereon, cutting mechanism carried by said head, means including a shaft carried by said frame for actuating said cutting mechanism, and means symmetrically disposed with respect to said 80 shaft for detachably connecting said head to said frame in different relative positions with respect to the latter.

4. In a mining machine, a frame having a forwardly extending mine bottom engaging portion, a head overlying said portion and in part supported thereon, cutting mechanism carried by said head, means carried by said frame for actuating said cutting mechanism, and means symmetrically disposed with respect to said actuating means for detachably connecting said head to said frame in different relative positions with respect to the latter, said cutting means being eccentrically disposed with respect to said 85 actuating means.

5. In a mining machine, a frame having a forwardly extending bottom engaging portion, a head overlying said portion and detachably secured to said frame and further in part supported by said forwardly extending portion and attachable to said frame in a plurality of positions, and cutting mechanism carried by said head.

6. In a mining machine, a frame having a forwardly extending bottom engaging portion, a head overlying said portion and detachably secured to said frame and attachable thereto in a plurality of positions, said 120 forwardly extending portion of said frame

also operating to support said head, cutting mechanism carried by said head, means carried by said frame for actuating said cutting mechanism, and means in said head for 5 operatively connecting said actuating means and cutting mechanism and engageable with said actuating means in any position of said head.

7. The combination with a mining machine having a cutter bar having cutting means extending from end to end thereof and invertible at will into positions substantially in the plane of the mine bottom or in a higher plane, of bar supporting means presenting a forwardly extending portion constantly connected to the machine and in either bar position underlying one end of the bar.

8. The combination with a mining machine having an elongated cutter bar pivoted adjacent one end for swinging movement about an axis lying in a vertical plane transverse to said machine and invertible at will into positions substantially in the plane of the mine bottom or in a higher plane, of bar supporting means presenting a forwardly extending portion constantly connected to the machine and in either bar position underlying the bar pivot.

9. The combination with a mining machine having an elongated cutter bar invertible at will into positions in different planes and having cutting means extending from end to end thereof, of bar supporting means presenting a forwardly extending portion non-rotatively mounted on said machine and in either bar position underlying one end of said bar.

10. The combination with a mining machine having a cutter bar invertible at will into positions in different planes and having cutting means extending from end to end thereof, of bar supporting means presenting a forwardly extending portion constantly connected to said machine and in either bar position slideable on a mine bottom beneath one end of said bar.

11. The combination with a mining machine having a cutter bar invertible at will into positions in different planes parallel to the mine bottom, said bar being provided with cutting means extending from end to end thereof, of bar supporting means forming a rigid support for one end of the bar constantly connected to the machine and in either position of the bar presenting a portion underlying the bar.

12. The combination with a mining machine having a cutter bar invertible at will into positions in different planes parallel to the mine bottom, of bar supporting means forming a rigid support for one end of the bar non-rotatably mounted on said machine and in either position of the bar presenting a portion slideable on the bottom beneath said 65 end of the bar.

13. The combination with a mining machine slideable over the mine bottom during cutting and having a pivoted cutter bar invertible at will into positions in different elevations relative to the mine bottom, of a machine frame having a forwardly extending portion, and a rigid member coaxial with the bar pivot supported at its opposite ends on said portion upon inversion of said bar and longitudinally removable in the different positions of said bar.

14. The combination with a machine having a cutter chain carrying cutter bar invertible at will into positions in different elevations relative to a mine bottom and having a frame providing a bottom engaging portion underlying one end of said bar in either position of the latter, of cutter chain driving mechanism in either position of said bar rigidly supported on said machine and accessible from the top of said bar.

15. The combination with a mining machine slideable over the mine bottom during cutting and having a cutter bar invertible at will into positions in different horizontal planes, of cutter actuating and supporting means including three longitudinally extending frame portions forming between them journal supports for the cutter driving mechanism and a cuttings passage.

16. In a mining machine, a frame, an invertible head thereon, cutting mechanism carried by said head, a bottom engaging shoe supporting said frame and extending beneath said head, and means for bracing said shoe and head in any position of the latter.

17. In a mining machine, a frame, a head detachably secured to said frame and attachable thereto in either of two relatively inverted positions, cutting mechanism carried by said head, a bottom engaging shoe supporting said frame and extending beneath said head, and means for connecting said shoe and head in either position of the latter.

18. In a mining machine, a frame, an invertible head thereon, cutting mechanism carried by said head, a shoe supporting said frame and extending beneath said head, and a vertical stud for bracing said shoe and head and detachably secured thereto to permit inversion of said head.

19. In a mining machine, a frame, an invertible head thereon, cutting mechanism carried by said head, a shoe supporting said frame and extending beneath said head, a removable plate carried by said head, a stud for bracing said shoe and head and detachably connected to said shoe, and a stud carried by said plate and having threaded connection with said first named stud.

20. In a mining machine, a frame, an invertible head thereon, cutting mechanism

- carried by said head, a shoe supporting said frame and extending beneath said head, a stud for bracing said shoe and head, a removable plate carried by said head, a removable plate carried by said shoe, and studs carried by said plates respectively and having threaded engagement with the opposite ends of said first named stud.
21. In a mining machine, a frame, an invertible head thereon, cutting mechanism carried by said head, a shoe supporting said frame and extending beneath said head, a stud for bracing said shoe and head, a removable plate carried by said head, a removable plate carried by said shoe, and studs carried by said plates respectively and having threaded engagement with the opposite ends of said first named stud.
22. In a mining machine, a frame, an invertible head thereon, cutting mechanism carried by said head, a shoe supporting said frame and extending beneath said head, said head in one position being seated on said shoe, and means for bracing said shoe and head in another position of the latter.
23. In a mining machine, a frame, an invertible head thereon, cutting mechanism carried by said head, a shoe supporting said frame and extending beneath said head, said head in one position being seated on said shoe, a vertical stud for bracing said shoe and head, and means for detachably securing said stud to said shoe and head.
24. In a mining machine, a frame, a removable, invertible head thereon, cutting mechanism carried by said head, a shoe supporting said frame and extending beneath the same, a removable plate carried by said shoe, a removable plate carried by said head and adapted to be seated on said first named plate when said head is in one position, a stud for bracing said shoe, means for detachably securing one end of said stud to said first named plate, and means for detachably connecting the opposite end of said stud to the other of said plates when said head is in its other position.
25. In a mining machine, a frame, a head carried thereby, cutting mechanism carried by said head and including a cutter chain sprocket journaled therein and having a bearing thereon, said cutting mechanism being disposable invertibly into different planes, and supplemental supporting means for said sprocket constantly connected to said frame.
26. In a mining machine, a frame having a forwardly extending, mine bottom engaging portion constantly connected thereto, a head detachably secured to said frame and portion and securable thereto in different relative positions, cutting mechanism carried by said head and portion and including rotating parts journaled in said head and having a bearing thereon, and means carried by said frame for actuating said cutting mechanism.
27. In a mining machine, a frame having a forwardly extending, mine bottom engaging portion, a head carried thereby and secured to said frame and portion and securable thereto in different relative positions, said head having a cylindrical boss, a cutter bar mounted to swing on said boss, a cutter chain carried by said bar, a cutter chain sprocket journaled in said boss, and a gear journaled in said boss and operatively connected to said sprocket.
28. In a mining machine, a frame, an invertible head thereon, a shoe supporting said frame and extending beneath said head, said head having a cylindrical boss, a cutter bar mounted to swing on said boss, a cutter chain carried by said bar, a cutter chain sprocket journaled in said boss, a gear journaled in said boss and operatively connected to said sprocket, a vertical stud for bracing said shoe and head and extending coaxially through said boss, cutter chain sprocket, and gear, and means for detachably securing said stud to said shoe and head.
29. In a mining machine, a frame slideable over the mine bottom during cutting and having a forwardly extending portion constantly connected thereto, a head carried thereby and secured to said frame and portion in different positions, and cutting mechanism carried by said head and including parts removable through the walls thereof.
30. In a mining machine, the combination with a feed operating member, an internal gear secured in fixed angular relation to said feed operating member and rotatable therewith, a motor driven pinion, an internal gear rotatable thereby, and variable speed driving connections between said internal gears.
31. In a mining machine, the combination with a feed operating member rotatable on a longitudinal axis, an internal gear secured in fixed angular relation to said feed operating member and rotatable therewith, a motor driven pinion rotatable on a longitudinal axis, an internal gear rotatable thereby, and variable speed driving connections between said internal gears.
32. In a mining machine, the combination with a feed operating member, an internal gear secured in fixed angular relation to said feed operating member and rotatable therewith, a motor driven pinion, an internal gear rotatable thereby, and variable speed driving connections between said internal gears including a friction clutch.
33. In a mining machine, the combination with a feed operating member, an internal gear secured in fixed angular relation to said feed operating member and rotatable therewith, a motor driven pinion, an internal gear journaled in said head and having a bearing thereon, and means car-

nal gear rotatable thereby, and variable speed driving connections between said internal gears including a friction clutch having an element rotatable with said second mentioned internal gear.

34. In a mining machine, the combination with a feed operating member, an internal gear secured in fixed angular relation to said feed operating member and rotatable therewith, a motor driven pinion, an internal gear rotatable thereby, and variable speed driving connections between said internal gears including a friction clutch and a cooperating clutch.

35. In a mining machine slidable upon a mine bottom, the combination with a feed operating member rotatable upon an axis extending longitudinally of the machine and adapted to cooperate with flexible feeding means in the feeding and guiding of a mining machine, of mechanism for driving the same including a motor, and driving connections between said motor and said member selectively operative to drive said feed operating member at a plurality of predetermined slow speeds in one direction or at a plurality of predetermined fast speeds in the opposite direction, all with the motor rotating in the same direction.

36. In a mining machine, the combination with a feed operating member adapted to cooperate directly with flexible feeding means and rotatable on an axis extending longitudinally of the machine, of mechanism for driving the same including a motor, and driving connections between said motor and said member selectively operative to drive said feed operating member at a plurality of predetermined slow speeds in one direction or at a plurality of predetermined fast speeds in the opposite direction, all with the motor rotating in the same direction, one of said slow speeds and one of said fast speeds being substantially twice as fast as its fellow.

37. In a mining machine, the combination with a feed operating member adapted to cooperate directly with flexible feeding means and rotatable on an axis extending longitudinally of the machine, of mechanism for driving the same including a motor, and driving connections between said motor and said member selectively operative to drive said feed operating member at a plurality of predetermined slow speeds in one direction or at a plurality of predetermined fast speeds in the opposite direction, all with the motor rotating in the same direction, and friction mechanism automatically operative to release each feed upon overload.

38. In a mining machine, the combination with a feed operating member adapted to cooperate directly with flexible feeding means, of mechanism for driving the same including a motor, and driving connections between

said motor and said member selectively operative to drive said feed operating member at a plurality of predetermined slow speeds in one direction or at a plurality of predetermined fast speeds in the opposite direction, and a single frictional device automatically operative to release any of said feeds upon overload.

39. In a mining machine, a feed operating member adapted to cooperate directly with flexible feeding means, a motor driven pinion, an internal gear meshing therewith, a main transmission shaft connectible with said gear, a plurality of countershafts operatively connected to said transmission shaft, a pinion rotatable by one of said countershafts, and an internal gear secured in fixed angular relation to and rotatable with said feed operating member and meshing with said last mentioned pinion.

40. In a mining machine, a feed operating member adapted to cooperate directly with flexible feeding means, a motor driven pinion, an internal gear meshing therewith, a main transmission shaft, a friction clutch controlling the connection thereof with said gear, a plurality of countershafts operatively connected to said transmission shaft, a pinion rotatable by one of said countershafts, and an internal gear secured in fixed angular relation to and rotatable with said feed operating member and meshing with said last mentioned pinion.

41. In a mining machine, a feed operating member adapted to cooperate directly with flexible feeding means, a motor driven pinion, an internal gear meshing therewith, a main transmission shaft connectible with said gear, a plurality of countershafts operatively connected to said transmission shaft and one connected to said feed operating member, and clutches controlling the connection of said internal gear to said transmission shaft and of said countershafts to one another.

42. In a mining machine, the combination with a feed operating member adapted to cooperate directly with flexible feeding means and rotatable upon an axis extending longitudinally of the machine, of means for actuating the same including a transmission shaft, a pair of aligned countershafts, means for operatively connecting said countershafts with each other, means for operatively connecting one of said countershafts with said feed operating member, and means for operatively connecting the other of said countershafts with said transmission shaft.

43. In a mining machine, the combination with a feed operating member adapted to cooperate directly with flexible feeding means and rotatable upon an axis extending longitudinally of the machine, of means for actuating the same including a transmission

shaft, a pair of alined countershafts, direct and reversible driving connections between said countershafts, means for operatively connecting one of said countershafts with 5 said feed operating member, and means for operatively connecting the other of said countershafts with said transmission shaft.

44. In a mining machine, the combination with a feed operating member adapted to 10 cooperate directly with flexible feeding means and rotatable upon an axis extending longitudinally of the machine, of means for actuating the same including a transmission shaft, a pair of alined countershafts, means 15 for operatively connecting said countershafts with each other including a transmission element on one of said countershafts, a clutch member on said last named countershaft and oppositely movable to engage alternatively said transmission element and the other of said countershafts, means for 20 operatively connecting one of said countershafts with said feed operating member, and means for operatively connecting the other 25 of said countershafts with said transmission shaft.

45. In a mining machine, the combination with a feed operating member adapted to cooperate directly with flexible feeding means 30 and rotatable upon an axis extending longitudinally of the machine, of means for actuating the same including a transmission shaft, a pair of alined countershafts, means for operatively connecting one of said countershafts with said feed operating member, variable power transmitting connections between said transmission shaft and the other of said countershafts, and variable power transmitting connections between said countershafts. 40

46. In a mining machine, the combination with a feed operating member adapted to cooperate directly with flexible feeding means and rotatable upon an axis extending longitudinally of the machine, of means for actuating the same including a transmission shaft, a pair of alined countershafts, said transmission shaft and countershafts being disposed with their axes in a common substantially vertical plane, means for operatively connecting said countershafts to each other, means for operatively connecting one of said countershafts with said feed operating member, and means for operatively connecting the other of said countershafts with said transmission shaft. 50

47. In a mining machine having cutting mechanism projecting from one end thereof and a feed operating member adapted to 60 cooperate directly with flexible feeding means and rotatable on an axis extending longitudinally of the machine frame at the opposite end of the latter from said cutting mechanism and effective on rotation to effect bodily rectilinear cutting feeding movement 65

of said machine, means for actuating the feed operating member comprising a motor shaft, a parallel transmission shaft, means for yieldingly connecting said shafts, and positive driving connections from said 70 transmission shaft to said feed operating member.

48. In a mining machine, the combination with cutting mechanism projecting from one end thereof and a feed operating member 75 adapted to cooperate directly with flexible feeding means and rotatable on an axis extending longitudinally of the opposite end of said machine from said cutting mechanism, of means for actuating the same comprising 80 a motor shaft, a parallel transmission shaft, means for yieldingly connecting said shafts, a countershaft, positive driving connections between said countershaft and feed operating member, and positive driving connections between said countershaft and transmission shaft. 85

49. In a mining machine, the combination with a feed operating member adapted to cooperate directly with flexible feeding means 90 and rotatable on a longitudinally extending axis, of means for actuating the same comprising a motor shaft, a transmission shaft, means for yieldingly connecting said shafts, a pair of alined countershafts, positive driving connections between said countershafts, positive driving connections between one of said countershafts and said feed operating member, and positive driving connections between the other of said countershafts and 95 said transmission shaft. 100

50. In a mining machine, the combination with a feed operating member adapted to cooperate directly with flexible feeding means and rotatable on a longitudinally extending axis, of means for actuating the same comprising a motor shaft, a transmission shaft, means for yieldingly connecting said shafts, a countershaft, positive driving connections between said countershaft and feed operating member, and positive variable speed driving connections between said countershaft and said transmission shaft. 105 110

51. In a mining machine, the combination with a feed operating member adapted to 115 cooperate directly with flexible feeding means and rotatable on a longitudinally extending axis, of means for actuating the same comprising a motor shaft, a transmission shaft, means for yieldingly connecting said shafts, a pair of alined countershafts, positive driving connections between one of said countershafts and said feed operating member, variable positive driving connections between the other of said countershafts and 120 said transmission shaft, and variable positive driving connections between said countershafts. 125

52. In a mining machine slideable upon a mine bottom, a machine frame having pro- 130

jecting from one end thereof cutting mechanism and having at the opposite end thereof of a feed operating member rotatable on an axis extending longitudinally of said frame, 5 flexible feeding means adapted to cooperate with said feed operating member and extending in a direction forwardly of said machine during cutting, and means for actuating said feed operating member to cause the 10 same to cooperate with said flexible feeding member to move the machine forwardly including an internal gear carried by said member and a pinion meshing with said gear.

53. In a mining machine, the combination with a feed operating member, of means for actuating the same including a transmission shaft, a pair of alined countershafts, means for operatively connecting said countershafts with each other, an internal gear carried by said feed operating member, a pinion carried by one of said countershafts and meshing with said gear, and means for operatively connecting the other of said countershafts with said transmission shaft.

54. In a mining machine, the combination with a frame and a rotatable feed operating member rotatable on an axis extending longitudinally of said frame, of means for actuating said feed operating member including an internal gear rotatable at an equal angular rate with said member and housed in said frame and a pinion meshing with said gear.

55. In a mining machine, the combination with a frame and a rotatable feed operating member having a bearing on said frame, of means for actuating said feed operating member including an internal gear rotatable with said member and extending into said frame and a pinion meshing with said gear and driving gearing for said pinion including another internal gear.

56. In a mining machine, a feed operating member rotatable on an axis extending longitudinally of said machine and adapted to cooperate with a flexible feeding member in moving the machine bodily toward a stationary point during cutting, and bearing means disposed at opposite ends of said member and carried by said machine including a horizontal bracket permitting access to opposite surfaces of said member.

57. In a mining machine, a frame having a boss, a bracket secured to said frame, a feed operating member having a hub extending in opposite directions into said boss and bracket, antifriction bearings for said hub carried by said boss and bracket respectively, 60 and cooperating flexible feeding member guiding means at opposite sides of said feed operating member.

58. In a mining machine, a frame having a boss, a bracket secured to said frame, a feed operating member having a hub, anti-

friction bearings for said hub carried by said boss and bracket respectively, and means for actuating said feed operating member including an internal gear rotatable with said member and extending into said frame and a pinion carried by said frame and meshing with said gear. 70

59. In a mining machine, a feed operating member rotatable on an axis extending longitudinally of said machine, bearing means at the opposite ends of said member carried on said machine and including a bracket permitting access to opposite surfaces of said member, and means for actuating said member including an internal gear rotatable therewith and a pinion meshing with said gear. 80

60. The combination with a mining machine truck having propelling means, of a mining machine transportable on said truck and having a rotary feed operating member rotatable on an axis extending longitudinally of said machine, means for actuating said feed operating member, and a member operated by said actuating means and arranged 90 coaxial with said feed operating member for driving said propelling means.

61. The combination with a mining machine truck having propelling means, of a mining machine transportable on said truck and having a feed operating member rotatable on an axis extending longitudinally of said machine, an internal gear carried by said feed operating member, means for actuating said feed operating member including a pinion meshing with said internal gear, and a member operated by said actuating means and arranged coaxially with said feed operating member and internal gear for driving said propelling means. 100

62. The combination with a mining machine truck having propelling means, of a mining machine transportable on said truck and having a frame, a feed operating member having a hub journaled in said frame, means for actuating said feed operating member, and a member journaled in said hub and operated by said actuating means for driving said propelling means. 110

63. The combination with a mining machine truck having propelling means, of a mining machine transportable on said truck and having a frame provided with a boss, a bracket secured to said frame, a feed operating member having a hub, antifriction 115 bearings for said hub carried by said boss and bracket respectively, means for actuating said feed operating member, and a member operated by said actuating means for driving said propelling means, said member being journaled in said hub and in the bearing carried by said bracket.

64. In a mining machine, a feed operating member rotatable on an axis extending longitudinally of the machine, and a plurality 120

of guide members rotatable on axes perpendicularly disposed relative to lines parallel to the axis of said member and disposed on opposite sides of a longitudinal plane extending through the axis of said feed operating member and perpendicularly disposed relative to the axes of said guiding members.

65. In a mining machine, a feed operating member rotatable on an axis extending longitudinally of the machine, and a plurality of guide members rotatable on axes perpendicularly disposed relative to lines parallel to the axis of said member and disposed on the same side of a vertical longitudinal plane extending through the axis of said feed operating member and respectively adapted to cooperate with the flexible feeding member at opposite sides of the point of cooperation with such member of said feed operating member.

66. In a mining machine, a feed operating member rotatable on an axis extending longitudinally of the machine, and a plurality of guide members rotatable on axes perpendicularly disposed relative to lines parallel to the axis of said member and disposed on the same side of a vertical longitudinal plane extending through the axis of said feed operating member and as to their guiding portions tangent to a common plane perpendicular to the axis of rotation of the feed operating member, one of said guide members being adapted to receive a flexible feeding member passing directly from said feed operating member.

67. In a mining machine, a feed operating member rotatable on an axis extending longitudinally of the machine, and a plurality of guide members rotatable on axes perpendicularly disposed relative to lines parallel to the axis of said member and disposed on the same side of a vertical longitudinal plane extending through the axis of said feed operating member, one of said guide members being adapted to receive a flexible feeding member passing directly from said feed operating member and the axes of said guiding members being so disposed as to lie in a single upright transverse plane.

68. In a mining machine, a feed operating member rotatable on an axis extending longitudinally of the machine, and a plurality of guide members rotatable on axes perpendicularly disposed relative to lines parallel to the axis of said member and disposed on the same side of a vertical longitudinal plane extending through the axis of said feed operating member, one of said guide members being adapted to receive a flexible feeding member passing directly from said feed operating member and the axes of said guiding members being so disposed as to lie

in transverse upright planes disposed beyond the end of said feed operating member.

69. In a mining machine, feeding means comprising a flexible feeding member, a feed operating member cooperating therewith, and a plurality of transferable members for guiding said flexible feeding member, each transferable into a plurality of positions to direct said flexible member through a plurality of paths whereby said machine may be fed during cutting according either to the room and pillar or longwall methods and in opposite directions.

70. In a mining machine, feeding means comprising a flexible feeding member, a feed operating member cooperating therewith, and a plurality of members for guiding said flexible feeding member, said guiding members being disposed at opposite ends of said machine and being attachable thereto at either side thereof to permit cutting in opposite directions.

71. In a mining machine, feeding means comprising a flexible feeding member, a feed operating member cooperating therewith, and a plurality of members for guiding said flexible member, said guiding members being disposed on parallel axes and one at the front end and two at the rear end of said machine and each on the same side of a vertical plane including the axis of said feed operating member and all cooperating with said flexible feeding member simultaneously during the feed of said machine.

72. In a mining machine, feeding means comprising a flexible feeding member, a feed operating member cooperating therewith, and a plurality of members for guiding said flexible member, said guiding members being disposed one at the front end and two at the rear end of said machine and each on the same side of a vertical plane including the axis of said feed operating member and transferable to the opposite side of said plane.

73. In a mining machine, feeding means comprising a flexible feeding member, a feed operating member cooperating therewith, and a plurality of members for guiding said flexible feeding member disposed in substantially the same transversely extending zone of the machine, said guiding members being disposed respectively adjacent the top and bottom of said machine and being attachable thereto at either side thereof.

74. In a mining machine, feeding means comprising a flexible feeding member, a feed operating member cooperating therewith, and a plurality of members for guiding said flexible feeding member, said guiding members being attachable to said machine at either side thereof and comprising a member at the forward end of said machine and a pair of members at the rear of said machine,

the latter disposed respectively adjacent the top and bottom thereof.

75. In a mining machine, the combination with a frame having lugs provided with apertures, of feeding means comprising a flexible feeding member, a feed operating member cooperating therewith, members for guiding said flexible feeding member, telescoping studs engaging said apertures and 10 by which said guiding members are carried, one of said studs having a groove, and a set screw carried by the other of said studs and engaging said groove for rotatably securing said studs together.

76. In a mining machine, feeding means comprising a flexible feeding member, a feed operating member cooperating therewith and a plurality of transferable bodily movably mounted members for guiding said 20 flexible feeding member disposable at will on opposite sides of a longitudinal vertical plane including the axis of said operating member.

77. In a mining machine, feeding means comprising a flexible feeding member, a feed operating member cooperating therewith, and a plurality of bodily movably mounted members for guiding said flexible feeding member, said guiding members being disposed respectively adjacent the top and bottom of said machine and being attachable thereto at either side thereof.

78. In a mining machine, feeding means comprising a flexible feeding member, a feed 35 operating member cooperating therewith, and a plurality of members each attachable to said machine in a plurality of positions theron for guiding said flexible feeding member, said members when attached to said 10 machine being mounted to swing about a common axis into a plurality of positions with respect to their positions of attachment.

79. In a mining machine, the combination 45 with a frame, of feeding means comprising a flexible feeding member, a feed operating member cooperating therewith, and a plurality of simultaneously operative detachably mounted members for guiding said flexible feeding member, said frame having a 50 plurality of supports intended respectively for each of said guiding members and to which said guiding members are attachable to guide said flexible member in different 55 positions of the latter.

80. In a mining machine, feeding means including a flexible feeding member, a rotary feed operating member operatively engaging said flexible feeding member and rotating 60 on an axis in a longitudinal vertical plane, and a plurality of rotary guide members on opposite sides of a longitudinal plane including the axis of said feed operating member and adapted to effect guiding of said 65 flexible feeding member, said feed operating

member and guide members being so disposed that planes including the pitch circles of said guide members are substantially tangent to the pitch circle of said feed operating member at different points.

81. In a mining machine, feeding means including a flexible feeding member, a rotary feed operating member operatively engaging said flexible feeding member, and a plurality of transferable rotary guide members 75 disposed at will in reverse relations to said feed operating member and so disposed in either position thereof that planes including the pitch circles of said guiding members are substantially tangent to the pitch 80 circle of said feed operating member.

82. In a mining machine, feeding means including a flexible feeding member, a rotary feed operating member operatively engaging said flexible feeding member and so disposed that the plane of its pitch circle makes an angle with a horizontal plane, and a plurality of rotary guide members on opposite sides of a longitudinal plane including the axis of said feed operating member 90 and adapted to effect guiding of said flexible feeding member, said feed operating member and guide members being so disposed that planes including the pitch circles of said guide members are substantially tangent to the pitch circle of said feed operating member at the top and bottom of the latter.

83. In a mining machine, feeding means including a flexible feeding member, a rotary feed operating member operatively engaging said flexible feeding member, and a plurality of rotary guide members on opposite sides of a longitudinal plane including the axis of said feed operating member and adapted to effect guiding of said flexible feeding member, said guiding members being disposed respectively adjacent the top and bottom of said machine and being attachable thereto at either side thereof and 100 said feed operating member and guide members being so disposed that planes including the pitch circles of said guide members are substantially tangent to the pitch circle of said feed operating member.

84. In a mining machine, feeding means including a flexible feeding member, a rotary feed operating member operatively engaging said flexible feeding member, and a plurality of coaxially disposed rotary guide 105 members adapted to effect guiding of said flexible feeding member, said feed operating and guiding members being so disposed that planes including the pitch circles of the guide members are substantially tangent to 120 the pitch circle of the feed operating member.

85. In a mining machine, feeding means including a flexible feeding member, a rotary feed operating member operatively en- 130

gaging said flexible feeding member and so disposed that the plane of its pitch circle makes an angle with a horizontal plane, and a plurality of coaxially disposed rotary 5 guide members adapted to effect guiding of said flexible feeding member, said feed operating and guiding members being so disposed that planes including the pitch circles of the guide members are substantially tangent to the pitch circle of the feed operating member at the top and bottom of the latter.

86. In a mining machine, feeding means including a flexible feeding member, a rotary feed operating member operatively engaging said flexible feeding member, and a plurality of rotary guiding members attachable to said machine in a plurality of positions thereon and adapted to guide said flexible member, said guide members when 15 attached to said machine being adapted to swing about a common axis into a plurality of positions with respect to their positions of attachment and said feed operating and guide members being so disposed that planes 20 including the pitch circles of said guide members are substantially tangent to the pitch circle of said feed operating member.

87. In a mining machine, feeding means including a flexible feeding member, a rotary feed operating member operatively engaging said flexible feeding member, and a plurality of axially spaced rotary guide members adapted to cooperate with said flexible feeding member, said feed operating 30 and guide members being so disposed that a plane including the pitch circle of said feed operating member is substantially tangent to the pitch circles of said guide members.

88. In a mining machine, feeding means including a flexible feeding member, a rotary feed operating member operatively engageable with said flexible feeding member, and a plurality of rotary guide members, 45 said feed operating and guide members being so disposed that planes including the pitch circles of said guide members are substantially tangent to the pitch circle of the feed operating member at different points and that a plane including the pitch circle of said feed operating member is substantially tangent to the pitch circles of said guide members.

89. In a mining machine, feeding means including a flexible feeding member, a rotatable feed operating member adapted to cooperate with said flexible feeding member, and a plurality of rotary guide members disposed one above the other and so disposable 55 that their axes may lie on opposite sides of a plane including the pitch circle of said feed operating member.

90. In a mining machine, feeding means including a flexible feeding member, a rotary feed operating member adapted to en-

gage said flexible feeding member, and a plurality of axially spaced rotary guide members adapted to guide said flexible feeding member, said guiding members being so disposed relative to said feed operating 70 member that a plane including the pitch circle of the latter is substantially tangent to the pitch circles of said guiding members and said guide members being disposable in positions at opposite sides of said plane and 75 there preserving a tangential relationship thereto.

91. In a mining machine, feeding means including a flexible feeding member, a rotary feed operating member operatively engaging said flexible feeding member, and a plurality of rotary guide members adapted to guide said flexible feeding member, said guide members being disposed respectively adjacent the top and bottom of said machine 80 and being attachable thereto at either side thereof and said guide members being also movable to positions at opposite sides of a plane including the pitch circuit of said feed operating member.

92. In a mining machine, feeding means including a flexible feeding member, a rotary feed operating member operatively engaging said flexible feeding member, and a plurality of rotary guide members adapted to guide said flexible feeding member, said guide members being so disposed relative to said feed operating member that planes including the pitch circles of said guide members are substantially tangent to the pitch circle of said feed operating member at different points and said guide members being movable to positions at opposite sides of a plane including the pitch circle of said feed operating member.

93. In a mining machine, feeding mechanism comprising a flexible feeding member, a feed operating member cooperating therewith and rotatable on an axis extending longitudinally of said machine, guide members adapted to receive said flexible member directly from said feed operating member and disposed on vertical axes, and an auxiliary guide member cooperating with said flexible member and with said first named guide members to load the machine and having its axis disposed in a vertical plane including the axis of said feed operating member.

94. In a mining machine, feeding mechanism comprising a flexible feeding member, a feed operating member cooperating therewith and rotatable on an axis extending longitudinally of said machine, guide members adapted to receive said flexible member directly from said feed operating member and disposed on vertical axes, and an auxiliary guide member cooperating with said flexible member and with said first named guide members to load the machine and having its axis disposed in a vertical plane including 120

the axis of the feed operating member, said auxiliary member being rotatable on an axis parallel to the axes of said guiding members.

- 5 95. In a mining machine, feeding mechanism comprising a flexible feeding member, a feed operating member cooperating therewith and rotatable on an axis extending longitudinally of said machine, guide members
 10 cooperating with said flexible feeding member during the mining operations and disposed on vertical axes, an auxiliary guide member cooperating with said flexible feeding member and with said first named guide members to load the machine, and means for detachably connecting said last named guide member to said machine.

96. In a mining machine, the combination with a frame, of feeding mechanism comprising a flexible feeding member, a feed operating member cooperating therewith and rotatable on an axis extending longitudinally of said machine, guide members cooperating with said flexible feeding member during the mining operations and disposed on vertical axes, an auxiliary guide member cooperating with said flexible feeding member and with said first named guide members to load the machine, and an arm by
 20 which said last named guide member is carried, said arm having means for loosely engaging the frame.

97. In a mining machine, the combination with a frame, of feeding means comprising a flexible feeding member, a feed operating member cooperating therewith, a plurality of detachably mounted guide members cooperating with said flexible feeding member during the mining operations, said frame having
 25 a plurality of supports to which each of said guide members is selectively attachable, an auxiliary guide member cooperating with said flexible feeding member to load the machine, and an arm by which said last named guide member is carried, said arm having means for selective detachable engagement with said supports.

98. In a mining machine, feeding mechanism comprising a flexible feeding member, a feed operating member cooperating therewith and rotatable on an axis extending longitudinally of said machine, guide members cooperating with said flexible feeding member during the mining operations and rotatable on vertical axes, and a swinging auxiliary guide member cooperating with said flexible feeding member to load the machine.

99. The combination with a mining machine slidable on a mine bottom and having flexible lateral feeding and machine guiding means including oppositely extending flexible feeding portions acting on the opposite ends thereof, of means whereby the plane of operation of said flexible feeding means may be varied with respect to said machine in-

cluding a guiding element disposable at different elevations above the mine bottom and disposed adjacent the forward end of the machine.

100. The combination with a mining machine slidable on a mine bottom having a cutter bar disposable in different elevations relative to the mine bottom without variation in the distance of the most remote portion of said machine from the mine bottom and flexible lateral feeding means including oppositely extending flexible feeding portions acting on the opposite ends of said machine, of means whereby the plane of forward traction of said flexible feeding means may be maintained in the plane of said bar.

101. The combination with a mining machine slidable on a mine bottom and having flexible lateral feeding means including oppositely extending flexible feeding portions acting on the opposite ends thereof to effect feeding and control the angle to the face, of means whereby the plane of forward traction and the direction of feed of said flexible feeding means may be varied including a guiding means for the flexible feeding means disposable at different elevations above the bottom.

102. The combination with a mining machine slidable on a mine bottom having a cutter bar disposable in different elevations relative to the mine bottom without variation in the distance of the most remote portion of said machine from the mine bottom and flexible lateral feeding means including oppositely extending flexible feeding portions acting on the opposite ends of said machine, of means whereby the plane of forward traction and the direction of feed of said flexible feeding means may be varied.

103. The combination with a mining machine slidable on a mine bottom having a pivoted laterally disposable cutter bar operable in different elevations relative to a mine bottom and flexible lateral feeding mechanism including a flexible feeding portion, of means whereby the plane of forward traction of said feeding mechanism may be varied in different positions of said bar.

104. The combination with a mining machine slidable on a mine bottom having a pivoted laterally disposable cutter bar adjustable into different elevations relative to a mine bottom and flexible lateral feeding mechanism including a flexible feeding portion, of means whereby the plane of forward traction and the direction of feed of said feeding mechanism may be adjusted in different positions of said bar.

105. The combination with a mining machine slidable on its bottom on a mine bottom and having a cutter bar disposable in different elevations relative to the mine bottom without change in elevation of the major

portion of said machine, of flexible lateral feeding mechanism having its plane of forward traction substantially in the plane of said bar in the different positions of the latter.

106. The combination with a mining machine slidable on its bottom on a mine bottom and having a cutter bar disposable in different elevations relative to the mine bottom without change in elevation of the major portion of said machine, of flexible lateral feeding mechanism including a flexible feeding portion and having its plane of forward traction substantially in the plane of said bar in the different positions of the latter.

107. The combination with a mining machine slidable on a mine bottom and having a single cutter bar disposable in different elevations relative to the mine bottom without change in elevation of the major portion of said machine, of flexible lateral feeding mechanism including flexible feeding portions acting on the opposite ends of said machine and having its plane of forward traction substantially in the plane of said bar in the different positions of the latter.

108. The combination with a mining machine slidable on a mine bottom and having a single cutter bar and operable at will as either a bottom cutter or an overcutter, of flexible lateral feeding mechanism for feeding said machine laterally in either operation thereof.

109. The combination with a mining machine slidable on a mine bottom and operable at will as either a bottom cutter or an overcutter and having a single pivoted laterally disposable cutter bar, of flexible feeding means for propelling said machine laterally in any bar position including a forward traction portion disposed in either plane of cut on said machine in substantially the plane of said bar.

110. The combination with a mining machine slidable on a mine bottom and operable at will as a bottom cutter or an overcutter and having at will during cutting a longitudinally extending or laterally disposable cutter bar, of flexible lateral feeding means disposable at will for room and pillar or longwall cutting.

111. The combination with a mining machine slidable on a mine bottom and operable at will as a bottom cutter or an overcutter and having at will during cutting a longitudinally extending or laterally disposable cutter bar, of flexible lateral feeding means disposable at will for room and pillar or longwall cutting and including a forward traction portion operable in either plane of cut substantially in the plane of said bar.

112. The combination with a mining machine slidable on a mine bottom and having a single pivotable cutter bar disposable in

different elevations from the bottom as either a room and pillar or a longwall bar, of flexible feeding mechanism for feeding said machine laterally in any bar position.

113. The combination with a mining machine slidable on a mine bottom and having a single pivotable cutter bar disposable in different elevations from the bottom as either a room and pillar or a longwall bar, of flexible feeding mechanism for feeding said machine laterally in any bar position and including a forward traction portion operable in each instance substantially in the plane of the bar.

114. In a mining machine, feeding means comprising a flexible feeding member, a rotary feed operating member providing means for operatively engaging said flexible feeding member, and a plurality of rotary guide members on opposite sides of a longitudinal plane including the axis of said feed operating member and adapted to effect guiding of said flexible feeding member, said rotary members being so disposed that planes including the pitch circles of said guiding members are parallel and are tangent to the pitch circle of said operating member.

115. In a mining machine, feeding means including a flexible feeding member, a rotary feed operating member operatively engaging said flexible feeding member, and a plurality of axially spaced rotary guide members adapted to cooperate with said flexible feeding member, said guide members being so mounted that their pitch circles may be tangent to a plane including the pitch circle of said feed operating member while said guide members are on the same side of said plane.

116. In a mining machine, feeding means including a flexible feeding member, a rotary feed operating member operatively engaging said flexible feeding member, and a plurality of axially spaced rotary guide members adapted to cooperate with said flexible feeding member, said guide members being so mounted that their pitch circles may be tangent to a plane including the pitch circle of said feed operating member while said guide members are on opposite sides of said plane.

117. In a mining machine, feeding means including a flexible feeding member, a rotary feed operating member operatively engaging said flexible feeding member, and a plurality of axially spaced rotary guide members adapted to cooperate with said flexible feeding member, said guide members being so mounted that their pitch circles may be tangent to a plane including the pitch circle of said feed operating member while said guide members are on the same or opposite sides of said plane.

118. In a mining machine, feeding means

including a flexible feeding member, a rotary feed operating member operatively engaging said flexible feeding member, and a plurality of axially spaced rotary guide members adapted to cooperate with said flexible feeding member, said guide members being so mounted that their pitch circles may be tangent to a plane including the pitch circle of said feed operating member while either of said guide members is at one side of said plane and the other at the other.

119. In a mining machine, feeding means including a flexible feeding member, a rotary feed operating member operatively engaging said flexible feeding member, and a plurality of axially spaced rotary guide members adapted to cooperate with said flexible feeding member, said guide members being so mounted that their pitch circles may be tangent to a plane including the pitch circle of said feed operating member while both of said guide members are at either side of said plane.

120. In a mining machine having a frame at one end of which a cutting mechanism is disposed, feeding mechanism including a flexible feeding member, a feed operating member adapted to cooperate therewith and rotating upon a longitudinally extending horizontal axis at the opposite end of said frame from said cutting mechanism, and a plurality of simultaneously operable guiding members for said flexible feeding member rotating upon vertical axes at the same end of said frame from one of which said flexible feeding member may pass directly to said feed operating member.

121. In a mining machine including a frame having cutting mechanism arranged at one end thereof, feeding mechanism including a flexible feeding member, a feed operating member rotatable upon a horizontal longitudinally extending axis at the opposite end of said frame from said cutting mechanism, and a plurality of guiding members adapted to cooperate with said flexible feeding member and rotating on vertical axes in part above and in part below a horizontal plane including said horizontal axis and arranged at the same end of said machine frame.

122. In a mining machine having a frame providing at one end cutting mechanism, feeding mechanism including a flexible feeding member, a feed operating member rotating upon a longitudinally extending horizontal axis at the end of said frame remote from said cutting mechanism, and guiding members adapted to cooperate with said flexible feeding member and rotating on parallel axes at the last mentioned end of the machine and in part on one side and in part on the other side of a horizontal plane including said horizontal axis.

123. In a mining machine, the combination with a feed operating member adapted to cooperate directly with flexible feeding means, an internal gear secured in fixed angular relation with the feed operating member and rotatable therewith, a second internal gear spaced longitudinally of said machine from said first mentioned internal gear, a motor driven pinion meshing with said second mentioned internal gear, and variable speed driving connections between said internal gears operative to effect rotation of the first mentioned internal gear at different speeds in opposite directions while said second mentioned internal gear rotates in the same direction and at uniform speed.

124. In a mining machine, the combination with a feed operating member adapted to cooperate directly with flexible feeding means, an internal gear secured in fixed angular relation with the feed operating member and rotatable therewith, a second internal gear spaced longitudinally of said machine from said first mentioned internal gear, a motor driven pinion meshing with said second mentioned internal gear, and variable speed driving connections between said internal gears operative to effect rotation of the first mentioned internal gear at different speeds in opposite directions while said second mentioned internal gear rotates in the same direction and at uniform speed, said variable speed driving connections including a plurality of cooperating elements all of which rotate on axes parallel to the axes of said internal gears or in alinement therewith.

125. In a mining machine, the combination with a feed operating member adapted to cooperate directly with flexible feeding means, an internal gear secured in fixed angular relation with the feed operating member and rotatable therewith, a second internal gear spaced longitudinally of said machine from said first mentioned internal gear, a motor driven pinion meshing with said second mentioned internal gear, and variable speed driving connections between said internal gears operative to effect rotation of the first mentioned internal gear at different speeds in opposite directions while said second mentioned internal gear rotates in the same direction and at uniform speeds, said variable speed driving connections including a plurality of cooperating elements all of which rotate on axes parallel to a line parallel to the axes of said internal gears and also including friction clutch mechanism including shippers slidable in directions parallel to said axes.

126. In a mining machine, the combination with a feed operating member adapted to cooperate directly with flexible feeding means, an internal gear secured in fixed angular relation with the feed operating mem-

ber and rotatable therewith, a second internal gear spaced longitudinally of said machine from said first mentioned internal gear, a motor driven pinion meshing with 5 said second mentioned internal gear, and variable speed driving connections between said internal gears operative to effect rotation of the first mentioned internal gear at different speeds in opposite directions while 10 said second mentioned internal gear rotates in the same direction and at uniform speed, said variable speed driving connections including a shaft extending from said second mentioned internal gear substantially to said 15 first mentioned internal gear and a plurality of shafts rotating on axes parallel to said first mentioned shaft and one carrying the pinion meshing with said first mentioned internal gear.

20 127. In a mining machine, the combination with a feed operating member adapted to cooperate directly with flexible feeding means, an internal gear secured in fixed angular relation with the feed operating member and rotatable therewith, a second internal gear spaced longitudinally of said machine from said first mentioned internal gear, a motor driven pinion meshing with 25 said second mentioned internal gear, variable speed driving connections between said internal gears operative to effect rotation of the first mentioned internal gear at different speeds in opposite directions while 30 said second mentioned internal gear rotates in the same direction and at uniform speed, said variable speed driving connections including a shaft extending from said second mentioned internal gear substantially to said 35 first mentioned internal gear, and a plurality of shafts rotating on aligned axes parallel to said first mentioned shaft and one carrying the pinion meshing with said first mentioned internal gear.

40 128. In a mining machine, a frame having a feed operating member thereon adapted to cooperate directly with flexible feeding means and rotatable on a longitudinally extending axis, and cooperating guiding members disposed on upstanding axes in horizontal planes above and below the axis of 45 said feed operating member.

129. In combination, a wheel supported truck body, a transverse shaft thereon and operatively connected to the wheels thereof, 55 and adapted to effect driving of the latter, mechanism mounted on said truck including a frame providing at one end cutting mechanism, and propulsion mechanism for said shaft including a driving member therefor 60 rotatable upon a horizontal longitudinally extending axis, a gear coaxial and rotatable therewith, an internal gear spaced longitudinally of said machine from said first mentioned gear, a motor driven pinion meshing 65 with said internal gear, variable speed driv-

ing connections between said gears operative to effect rotation of the first mentioned gear at different speeds in either direction while said second mentioned gear rotates in the same direction and at uniform speed. 70

130. In combination, a wheel supported truck body, a transverse shaft thereon operatively connected to the wheels thereof and adapted to effect driving of the latter, mechanism mounted on said truck including a frame providing at one end cutting mechanism, and propulsion mechanism for said shaft including a driving member therefor 75 rotatable upon a horizontal longitudinally extending axis, a gear coaxial and rotatable therewith, an internal gear spaced longitudinally of said machine from said first mentioned gear, a motor driven pinion meshing with said internal gear, variable speed driving connections between said gears operative to effect rotation of the first mentioned gear at different speeds in either direction while 80 said second mentioned gear rotates in the same direction and at uniform speed, said variable speed driving connections including a plurality of cooperating elements all of which rotate on axes parallel to the axes of said gears or in alignment therewith. 85

131. In combination, a wheel supported truck body, a transverse shaft thereon operatively connected to the wheels thereof and adapted to effect driving of the latter, mechanism mounted on said truck including a frame providing at one end cutting mechanism, and propulsion mechanism for said shaft including a driving member therefor 90 rotatable upon a horizontal longitudinally extending axis, a gear coaxial and rotatable therewith, an internal gear spaced longitudinally of said machine from said first mentioned gear, a motor driven pinion meshing with said second mentioned gear, and variable speed driving connections between said gears operative to effect rotation of the first mentioned gear at different speeds in either direction while 95 said second mentioned gear rotates in the same direction and at uniform speed, said variable speed driving connections including a plurality of cooperating elements all of which rotate on axes parallel to the axes of said gears or in alignment therewith. 100

132. In combination, a wheel supported truck body, a transverse shaft thereon operatively connected to the wheels thereof and adapted to effect driving of the latter, mechanism mounted on said truck including a frame providing at one end cutting mechanism, and propulsion mechanism for said shaft including a driving member therefor 110 rotatable upon a horizontal longitudinally extending axis, a gear coaxial and rotatable therewith, an internal gear spaced longitudinally of said machine from said first mentioned gear, a motor driven pinion meshing with said second mentioned gear, and variable speed driving connections between said gears operative to effect rotation of the first mentioned gear at different speeds in either direction while 115 said second mentioned gear rotates in the same direction and at uniform speed, said variable speed driving connections including a plurality of cooperating elements all of which rotate on axes parallel to the axes of said gears or in alignment therewith. 120

nally of said machine from said first mentioned gear, a motor driven pinion meshing with said internal gear, and variable speed driving connections between said gears operative to effect rotation of the first mentioned gear at different speeds in either direction while said second mentioned gear rotates in the same direction and at uniform speed, said variable speed driving connections including a shaft extending from said second mentioned gear substantially to said first mentioned gear and a plurality of shafts rotating on axes parallel to said second mentioned shaft and one carrying the pinion meshing with said first mentioned gear.

133. In combination, a wheel supported truck body, a transverse shaft thereon operatively connected to the wheels thereof and adapted to effect driving of the latter, mechanism mounted on said truck including a frame providing at one end cutting mechanism, and propulsion mechanism for said shaft including a driving member therefor rotatable upon a horizontal longitudinally extending axis, a gear coaxial and rotatable therewith, an internal gear spaced longitudinally of said machine from said first mentioned gear, a motor driven pinion meshing with said second mentioned gear, variable speed driving connections between said gears operative to effect rotation of the first mentioned gear at different speeds in either direction while said second mentioned gear rotates in the same direction and at uniform speed, said variable speed driving connections including a shaft extending from said second mentioned gear substantially to said first mentioned gear, and a plurality of shafts rotating on aligned axes parallel to said second mentioned shaft and one carrying the pinion meshing with said first mentioned gear.

134. In a mining apparatus, mining mechanism including a machine casing slidable on its bottom on a mine bottom and a cutter chain carrying cutter bar pivotally mounted on one end thereof and disposable longitudinally thereof or laterally, and flexible feeding means acting on said machine at a point below the plane of said bar for propelling said casing and bar laterally to form a kerf in a face.

135. In a mining apparatus, mining mechanism including a machine casing slidable on its bottom on a mine bottom and a cutter chain carrying cutter bar pivotally mounted on one end thereof and disposable longitudinally thereof or laterally at either side thereof, and flexible feeding means acting on said machine at a point below the plane of said bar for propelling said casing and bar laterally to form a kerf in a face.

136. In a mining apparatus, mining mechanism including a machine casing slidable on its bottom on a mine bottom and a piv-

otally mounted cutter chain carrying cutter bar projecting from one end thereof in a plane adjacent the upper surface of said casing, and means whereby said machine may be utilized as a room and pillar or longwall machine at will including flexible feeding means acting in either relation on said machine at a point beneath the plane of said bar to propel the latter laterally to form a kerf in a face.

137. In a mining apparatus, a mining mechanism including a casing slidable on its bottom on a mine bottom and a cutter chain carrying cutter bar pivotally mounted on one end thereof and disposable in fixed positions longitudinally or laterally thereof in a plane substantially coincident with the upper surface of said casing, and flexible feeding means acting on said machine at a point below the plane of said bar for propelling said casing and bar laterally to form a kerf in a face.

138. In a mining machine, mining mechanism including a machine casing slidable on its bottom on a mine bottom and a pivoted cutter chain carrying cutter bar rigidly connected thereto and extending longitudinally thereof, and flexible feeding means for propelling said casing and bar laterally to form a kerf in a face including guiding means adjacent the opposite ends of said casing in a plane substantially parallel to and adjacent the mine bottom and below the plane of said bar.

139. In a mining apparatus, a mining mechanism including a casing slidable on its bottom on a mine bottom and a cutter chain carrying cutter bar pivotally mounted on one end thereof and disposable in fixed positions longitudinally or laterally thereof in a plane substantially coincident with the upper surface of said casing, and flexible feeding means in either relation acting on said machine at a point below the plane of said bar for propelling said casing and bar laterally to form a kerf in a face, said means including a removable guiding member disposed adjacent the pivot of said bar.

140. In a mining apparatus, a mining mechanism including a casing slidable on its bottom on a mine bottom and a cutter chain carrying cutter bar pivotally mounted on one end thereof and disposable in fixed positions longitudinally or laterally thereof in a plane substantially coincident with the upper surface of said casing, and flexible feeding means in either relation acting on said machine at a point below the plane of said bar for propelling said casing and bar laterally to form a kerf in a face, said means including a removable guiding member disposed adjacent the pivot of said bar and a feed operating member nearer the opposite end of said casing.

141. In a mining machine, mining mech-

- anism including a mining machine casing 65
slidable on its bottom on a mine bottom and a pivoted cutter chain carrying cutter bar on one end thereof disposed in a plane substantially coincident with the top of the machine casing and adjustable into fixed positions longitudinally or laterally relative thereto, a guiding member disposed adjacent the bottom of said casing and beneath the 10 plane of said bar, and means for attaching said guiding member in any one of a plurality of positions adjacent the pivot of said bar.
142. In a mining machine, mining mechanism 15 including a mining machine casing slidable on its bottom on a mine bottom and having a front head provided with radially located apertures, an apertured cutter chain carrying cutting bar pivoted on said head and having its aperture movable into registry with the apertures in said head, said bar being disposed in a plane substantially coinciding with the top of said casing and above the apertures in said head, adjustable 20 means receivable in the apertures in said head and bar for retaining said bar in different positions of adjustment, and guiding means for flexible feeding means carried in an aperture in said head and disposed in a 25 plane below said bar.
143. In a mining apparatus, a mining machine including a machine frame slidably supported upon a mine bottom and a cutter chain carrying cutter bar pivotally mounted 30 on one end of said frame and disposable longitudinally of the latter or laterally, and flexible feeding means acting in a plane below the plane of said bar for propelling said frame and bar transversely of a face during 35 cutting with said bar in different angular positions relative to said frame, including a position longitudinal thereof.
144. In a mining apparatus, a mining mechanism including a machine frame slidably supported on a mine bottom and a single pivoted cutter chain carrying cutter bar mounted on said frame substantially in the same plane as the top of said frame, and feeding mechanism comprising flexible feeding 40 portions lying wholly in and acting in a horizontal plane below the plane of said bar and feed operating means cooperating therewith to vary the lengths of said portions.
145. In a mining apparatus, a mining machine slidable over a mine bottom including a motor whose power shaft lies approximately in the central horizontal plane of said machine, a bevel pinion on said shaft, a horizontal bevel gear below and meshing with 45 said pinion, a spur pinion rotatable with said bevel gear, a cutter chain driving sprocket, a gear coaxial with said sprocket and meshing with said spur pinion, and a cutter chain carrying cutter bar carrying a chain driven by 50 said sprocket and swinging upon a pivot coaxial with said spur gear.
146. In a mining apparatus, a mining machine slidable over a mine bottom including a motor whose power shaft lies approximately in the central horizontal plane of 55 said machine, a bevel pinion on said shaft, a horizontal bevel gear below and meshing with said pinion, a spur pinion rotatable with said bevel gear, a cutter chain driving sprocket, a gear coaxial with said sprocket and meshing with said spur pinion, and a cutter chain carrying cutter bar carrying a chain driven by 60 said sprocket and swinging upon a pivot coaxial with said spur gear.
147. In a mining apparatus, a mining machine slidable over a mine bottom including a motor whose power shaft lies approximately in the central horizontal plane of 65 said machine, a bevel pinion on said shaft, a vertically pivoted bevel gear meshing with said pinion, a spur pinion rotatable with said bevel gear, a cutter chain driving sprocket above said spur pinion, a gear coaxial with said sprocket and meshing with 70 said spur pinion, and a cutter chain carrying cutter bar carrying a chain driven by 75 said sprocket.
148. In a mining apparatus, a mining machine slidable over a mine bottom including a motor whose power shaft lies approximately in the central horizontal plane of 80 said machine, a bevel pinion on said shaft, a vertically pivoted bevel gear meshing with said pinion, a spur pinion rotatable with said bevel gear, a cutter chain driving sprocket above said spur pinion, a gear coaxial with said sprocket and meshing with 85 said spur pinion, and a cutter chain carrying cutter bar carrying a chain driven by 90 said sprocket.
149. In a mining apparatus, a mining machine slidable over a mine bottom and including a motor having a horizontal power shaft carrying a bevel pinion at one end thereof, a bevel gear driven by said bevel pinion, a spur pinion coaxial with and rotated by said bevel gear, a spur gear rotating on a parallel axis and driven by said 95 spur pinion, a cutter chain driving sprocket coaxial with said spur gear, and a cutter chain driven by said sprocket, said spur gear and pinion and said bevel gear all rotating 100 on vertical axes and the first two being disposed above the plane of the last.
150. In a mining apparatus of the type which is slidable over the mine bottom during cutting, a motor, cutting mechanism driven thereby including a pivoted cutter bar having a circulating cutter chain to which circulating movement is transmitted 105 from one end of said motor, and feeding means driven from the other end of said 110
- 120
- 125

- motor including a rotatable feed operating member adapted to cooperate directly with a flexible feeding element during feed, a power transmitting member rotating on a horizontal axis extending longitudinally of the mining apparatus and constituting a driving element for said feed operating member, said feed operating member having coaxial therewith and fixed relative thereto
- 5 10 a driving gear member and said horizontal axis being spaced a less distance from the axis of said driving gear than the pitch radius of the latter, and means for rotating said power transmitting member including
- 15 a shaft coaxial therewith, a plurality of toothed driving members for said shaft coaxial with the latter and disposed with their respective teeth in different transverse zones with respect to said shaft and selectively
- 20 connectible to said shaft to effect rotation thereof at different predetermined speeds and means for selectively effecting such connection.

151. In a mining apparatus of the type
- 25 which is slidable over the mine bottom during cutting, a motor, cutting mechanism driven thereby including a pivoted cutter bar having a circulating cutter chain to which circulating movement is transmitted
- 30 from one end of said motor, and feeding means driven from the other end of said motor including a rotatable feed operating member adapted to cooperate directly with a flexible feeding element during feed, a
- 35 power transmitting member rotating on a horizontal axis extending longitudinally of the mining apparatus and constituting a driving element for said feed operating member, said feed operating member having
- 40 coaxial therewith and fixed relative thereto a driving gear member and said horizontal axis being spaced a less distance from the axis of said driving gear than the pitch radius of the latter, and means for rotating
- 45 said power transmitting member including a shaft coaxial therewith, a plurality of toothed driving members for said shaft coaxial with the latter and disposed with their respective teeth in different transverse zones
- 50 with respect to said shaft and selectively connectible to said shaft to effect rotation thereof at different predetermined speeds and clutch means coaxial with said shaft for selectively effecting such connection.
- 55 152. In a mining apparatus of the type
- 60 which is slidable over the mine bottom during cutting, a motor, cutting mechanism driven thereby including a pivoted cutter bar having a circulating cutter chain to which
- 65 circulating movement is transmitted from one end of said motor, and feeding means driven from the other end of said motor including a rotatable feed operating member adapted to cooperate directly with a flexible

feeding element during feed, a power transmitting member rotating on a horizontal axis extending longitudinally of the mining apparatus and constituting a driving element for said feed operating member, said feed operating member having coaxial therewith and fixed relative thereto a driving gear member and said horizontal axis being spaced a less distance from the axis of said driving gear than the pitch radius of the latter, and means for rotating said power transmitting member including a shaft coaxial therewith, a plurality of toothed driving members for said shaft coaxial with the latter and disposed with their respective teeth in different transverse zones with respect to said shaft and selectively connectible to said shaft to effect rotation thereof at different predetermined speeds and clutch means coaxial with said shaft and oppositely movable to effect such selective connection.

153. In a mining apparatus of the type which is slidable over the mine bottom during cutting, a motor, cutting mechanism driven thereby including a pivoted cutter bar having a circulating cutter chain to which circulating movement is transmitted from one end of said motor, and feeding means driven from the other end of said motor including a feed operating member rotatable on an axis disposed in a vertical plane extending longitudinally of said apparatus adapted to cooperate directly with a flexible feeding element during feed, a power transmitting member rotating on a horizontal axis extending longitudinally of the mining apparatus and constituting a driving element for said feed operating member, said feed operating member having coaxial therewith and fixed relative thereto a driving gear member and said horizontal axis being spaced a less distance from the axis of said driving gear than the pitch radius of the latter, and means for rotating said power transmitting member including a shaft coaxial therewith, a plurality of toothed driving members for said shaft coaxial with the latter and disposed with their respective teeth in different transverse zones with respect to said shaft and selectively connectible to said shaft to effect rotation thereof at different predetermined speeds and means for selectively effecting such connection.

154. In a mining apparatus of the type which is slidable over the mine bottom during cutting, a motor, cutting mechanism driven thereby including a pivoted cutter bar having a circulating cutter chain to which circulating movement is transmitted from one end of said motor, and feeding means driven from the other end of said motor including a feed operating member rotatable on an axis disposed in a vertical

- plane extending longitudinally of said apparatus adapted to cooperate directly with a flexible feeding element during feed, a power transmitting member rotating on a 5 horizontal axis extending longitudinally of the mining apparatus and constituting a driving element for said feed operating member, said feed operating member having coaxial therewith and fixed relative thereto a driving gear member and said horizontal axis being spaced a less distance from the axis of said driving gear than the pitch radius of the latter, and means for rotating said power transmitting member 10 including a shaft coaxial therewith, a plurality of toothed driving members for said shaft coaxial with the latter and disposed with their respective teeth in different transverse zones with respect to said shaft and selectively connectible to said shaft to effect rotation thereof at different predetermined speeds and clutch means coaxial with said shaft for selectively effecting such connection.
- 15 155. In a mining apparatus of the type which is slidable over the mine bottom during cutting, a motor, cutting mechanism driven thereby including a pivoted cutter bar having a circulating cutter chain to 20 which circulating movement is transmitted from one end of said motor, and feeding means driven from the other end of said motor including a feed operating member rotatable on an axis disposed in a vertical 25 plane extending longitudinally of said apparatus adapted to cooperate directly with a flexible feeding element during feed, a power transmitting member rotating on a horizontal axis extending longitudinally of the mining apparatus and constituting a driving element for said feed operating member, said feed operating member having coaxial therewith and fixed relative thereto a driving gear member and said horizontal axis 30 being spaced a less distance from the axis of said driving gear than the pitch radius of the latter, and means for rotating said power transmitting member including a shaft coaxial therewith, a plurality of 35 toothed driving members for said shaft coaxial with the latter and disposed with their respective teeth in different transverse zones with respect to said shaft and selectively connectible to said shaft to effect rotation thereof at different predetermined speeds and clutch means coaxial with said shaft for selectively effecting such connection.
- 40 156. In a mining machine, a machine frame having cutting mechanism projecting therefrom at one end thereof, and feeding mechanism for moving said frame and cutting mechanism bodily in a direction substantially parallel to a working face during cutting including a feed operating member 45 adapted to cooperate directly with a flexible feeding element and rotatable on an axis extending longitudinally of the machine frame and disposed at the other end of the latter, and means for actuating said feed operating member comprising a motor shaft, a transmission shaft adapted to be driven directly by the motor shaft, means for yielding connecting said shafts, and positive driving connections from said transmission 50 shaft to said feed operating member.
157. In a mining machine, a machine frame having cutting mechanism projecting therefrom at one end thereof, and feeding mechanism for moving said frame and cutting mechanism bodily in a direction substantially parallel to a working face during cutting including a feed operating member 55 adapted to cooperate directly with a flexible feeding element and rotatable on an axis extending longitudinally of the machine frame, and bearing means disposed at opposite ends of said member and carried by said machine including a longitudinally extending bracket permitting access to opposite surfaces of 60 said member.
158. The combination with a mining machine having a body slidable on its bottom directly on the mine bottom and having a single cutter bar selectively disposable at 65 different elevations relative to the mine bottom to enable the machine to cut in different planes including a position substantially on the bottom, and flexible feeding mechanism for feeding said machine relative to the coal face in any position of said bar.
159. The combination with a mining machine having a body slidable on its bottom directly on the mine bottom and having a single cutter bar selectively disposable in 70 different elevations from the mine bottom to enable the machine to cut in different planes, and flexible feeding mechanism for feeding said machine relative to the coal face in any 75 position of said bar including a feed operating member rotatable on a horizontal axis extending longitudinally of the machine and adapted to cooperate with a flexible feeding element.
160. In a mining apparatus, a transport truck, a mining machine adapted to be supported thereon and having a motor, feeding means for the machine including a feed operating member adapted to cooperate with 80 flexible feeding means, truck driving means including a rotatable element on the machine arranged coaxially with and rotatable relative to said feed operating member during driving of the truck and adapted to make an operative connection with truck driving mechanism on the truck, and driving connections between said motor and said feed operating member and truck driving element.

161. In a mining apparatus, a transport truck, a mining machine adapted to be supported thereon and having a motor, feeding means for the machine including a feed operating member adapted to cooperate with flexible feeding means, truck driving means including a rotatable element on the machine arranged coaxially with and rotatable relative to said feed operating member during truck drive and adapted to make an operative connection with truck driving mechanism on the truck, and driving connections between said motor and said feed operating member and truck driving element for simultaneously rotating the same including gears individual to each of the same.

162. In a mining apparatus, a transport truck, a mining machine adapted to be supported thereon and having a motor, feeding means for the machine including a feed operating member adapted to cooperate with flexible feeding means, truck driving means including a rotatable element on the machine arranged coaxially with and rotatable relative to said feed operating member and adapted to make an operative connection with truck driving mechanism on the truck, and driving connections between said motor and said feed operating member and truck driving element for simultaneously rotating the same at different speeds in opposite directions.

163. In a mining apparatus, a transport truck, a mining machine thereon having a driving motor and truck propelling means driven by said motor including a rotatable truck driving element rotatable on an axis extending longitudinally of the machine, and driving connections between said motor and said element selectively operative to drive

the same at a plurality of predetermined slow speeds in one direction or at a plurality of predetermined fast speeds in the opposite direction with the motor in each case running in the same direction at the same speed. 45

164. In a mining apparatus, a transport truck, a mining machine thereon having a driving motor and truck propelling means driven by said motor including a rotatable truck driving element rotatable on an axis 50 extending longitudinally of the machine, and driving connections between said motor and said element selectively operative to drive the same at a plurality of predetermined slow speeds in one direction or at a plurality of predetermined fast speeds in the 55 opposite direction with the motor in each case running in the same direction at the same speed, one of said slow speeds and one of said fast speeds being substantially twice as fast as its fellow. 60

165. In a mining apparatus, a transport truck, a mining machine thereon having a driving motor and truck propelling means driven by said motor including a rotatable truck driving element rotatable on an axis 65 extending longitudinally of the machine, driving connections between said motor and said element selectively operative to drive the same at a plurality of predetermined slow speeds in one direction or at a plurality of predetermined fast speeds in the 70 opposite direction with the motor in each case running in the same direction at the same speed, and friction mechanism automatically operative to release each speed upon overload. 75

In testimony whereof I affix my signature.

MORRIS P. HOLMES.

CERTIFICATE OF CORRECTION.

Patent No. 1,662,789.

Granted March 13, 1928, to

MORRIS P. HOLMES.

It is hereby certified that error appears in the printed specification of the above numbered patent requiring correction as follows: Page 15, line 89, claim 91, for the word "circuit" read "circle"; page 19, lines 104 and 105, claim 131, for the misspelled word "longitudinaly" read "longitudinally"; page 21, line 19, claim 142, for the word "cutting" read "cutter"; and that the said Letters Patent should be read with these corrections therein that the same may conform to the record of the case in the Patent Office.

Signed and sealed this 10th day of April, A. D. 1928.

(Seal)

**M. J. Moore,
Acting Commissioner of Patents.**
